UNITED STATES PATENT OFFICE.

LEWIS F. GRISWOLD, OF MERIDEN, CONNECTICUT, ASSIGNOR TO THE CHARLES PARKER COMPANY, OF CONNECTICUT.

DESIGN FOR A PIANO-CHAIR.

SPECIFICATION forming part of Design No. 25,183, dated February 18, 1896.

Application filed October 19, 1895. Serial No. 566,271. Term of patent 14 years.

To all whom it may concern:

Be it known that I, LEWIS F. GRISWOLD, of Meriden, in the county of New Haven and State of Connecticut, have invented a certain 5 new and useful Design for a Piano-Chair; and I do hereby declare that the following is a full, clear, and exact description of the same, reference being had to the accompanying drawing, forming part of this specification.

10 My invention relates to a design for that kind of piano chairs in which there is a seat-supporting, horizontal part having suitable legs and provided with a back, and over which is mounted a revoluble seat.

15 The accompanying drawing, which forms part of this specification, presents a perspective view of the new design of chair.

In the drawing, A is the revoluble and vertically-adjustable seat, the centrally-depend- 20 ing stem of which is mounted in a central column b, that projects downwardly from the middle portion of the plate-like part C of the chair. This part C is supported on four legs d, which have their upper ends secured there- 25 to, as shown, and which have ornamental feet f, and which are connected, as seen, by four short fancy-shaped rounds e to the central column b.

The contour of the part C is such that a 30 portion of its perimeter is circular and concentric to the circular perimeter of seat A, but it is formed with a laterally-projecting portion G at the back side of the chair, from which rearwardly-projecting portion (near its 35 edge) ascends the back of the chair II. This back comprises, essentially, two turned standards h h, a fancy-shaped back board L, (connecting h h near their upper ends,) and a series of small bars i, all as clearly shown.

40 All the members b, d and e are shown as turned stock, while the edges of the plate-like portion C and the seat A are represented as being beaded.

The parts h and i of the back are arranged 45 so that in horizontal section they present a general contour approximately correspond-

to the contour of the seat's perimeter, and the parts h h diverge slightly as they ascend from G, while the back board L connecting their upper portions is curved in horizontal 50 section. This part L is shown as having a sort of arched top edge, the line of which comprises a nearly semicircular middle portion and ogee curves extending thence toward each bar h; but these details of the design 55 are not important.

The characteristic feature or main novelty of the design lies in the configurations of the seat A and part C, the perimeters of which present concentric curves, but with the seat's 60 perimeter overhanging or extending beyond that of the part C and the latter projecting rearwardly at G, so that the back member II of the design ascends from the rearward part of the projection G. It will be observed that 65 this characteristic feature lends a new and unique appearance to this species of piano-chair, and it will be understood that this novel feature may easily be embodied in a chair the patterns of the turned parts b, d, e 70 and h of which might be quite different from those shown, and the back II of which might be of some other design than that shown. I therefore wish it to be understood that my invention lies in the broad characteristic fea- 75 ture of such configuration of the chair as presents the members A and C conforming in contour except as to the projection G of the latter, but with the former larger than the latter, and a back member II ascending from 80 the rearmost portion of the projection G and outside the perimeter of A.

What I claim as new, and desire to secure by Letters Patent, is—

A design for a piano-chair substantially 85 as herein shown and described.

In witness whereof I have hereunto set my hand this 3d day of July, 1895.

LEWIS F. GRISWOLD.

In presence of—

R. A. PALMER,
D. W. PARKER.
